UNITED STATES PATENT OFFICE.

ARTHUR R. MASON AND OTTO C. FAILING, OF MEDFORD, OREGON, ASSIGNEES TO
ACCURATE GASOLINE RECORDING COMPANY, A CORPORATION OF OREGON.

SAFETY MEANS FOR FLUID-DISPENSING PUMPS.

Application filed August 17, 1927. Serial No. 213,689.

Our invention has for its principal object means for furnishing a customer and a salesman each with a check or printed slip showing the amount of fluid dispensed from a 5 pump for each completed transaction, and wherein a further slip or paper strip is retained within the mechanism and has registered thereon the consecutive transactions and indicates at any time not only the fluid 10 dispensed on each consecutive transaction, but also the total fluid dispensed on all previous operations.

It is also applicable to recording trade 15 transactions generally wherein a paper strip is delivered from any sales mechanism our invention providing that said strip is first produced within a closed compartment and until the transaction is completed, at which time the cutting of the strip releases and exposes the strip from the locked means.

In this way the customer is insured against 20 an incorrect record different from the goods dispensed on his purchase and is secured a slip record for the full amount of his purchase. Thus where a customer drives up to 25 a conventional gasoline station and asks to have his automobile tank filled with gasoline it is not necessary for him to leave the driver's seat to insure the quantity of gasoline for 30 which he pays being pumped into the tank. This is attained through the mechanism of our invention which reels off a paper strip of a length proportional to the amount of gasoline pumped and which strip, when the 35 transaction is completed, is cut and presented to the purchaser showing by its length and any suitable characters and/or scale printed thereon, the amount of gasoline which the pump has just delivered.

40 Other objects will appear from the drawing and specifications which follow:

In the drawing, Fig. 1 represents a conventional oil or gasoline pump as employed in filling stations.

45 Fig. 2 is a front view of our safety casing in its closed position.

Fig. 3 is a section of Fig. 2 on the line III-III thereof, with the casing shown in its opened position.

50 Fig. 4 is a detail of the cutting knife.

Fig. 5 is a section on the line V-V of Fig. 2.

Throughout the figures, similar numerals refer to identical parts.

55 The numeral 1 indicates a pump column

and 2 a piston operating therein as in a conventional gasoline or lubricating oil pump.

At 3 is the storage supply from which the pump abstracts fluid upon the rotation of the handle 8 through which the rack 7 raises the 60 piston 2.

Fluid is delivered through the pipe 5 to the chamber 6 and thence is dispensed through the spout 4.

The front of the box housing the pump 65 operating mechanism is provided with a delivery slot 14 for the discharge of an unreeled portion of a paper strip or strips corresponding in length to the quantity of fluid discharged by the pump in each sales transaction. This slot is normally housed completely by the casing 11 so that the paper strip is inaccessible until it is sheared or cut off when the housing automatically opens and the strip is discharged, completing the 75 sales transaction.

The delivery slot 14 is provided on its top with a cutting edge engaging the shear blade 16 thereby shearing the paper strip with a smooth clean cut, while the bottom 80 edge of this delivery slot is provided with a toothed or serrated edge 23 whereby, should the operator attempt to pull out the paper strip without operating the pump the sharp teeth will engage the paper strip and tear it 85 off in a zig-zag manner disclosing misuse.

The numeral 10 indicates a box member containing our mechanism whose actuating upon the rotation of the handle 8 operates the paper strips.

This mechanism is fully set forth in our co-pending application Serial No. 213,688, filed Aug. 17, 1927, to which reference is herein made.

The present invention refers more specifically to the control and delivery of the paper or record strips after they are produced by the said mechanism.

At 11 is a safety casing having a glass front 12 hinged at 13 and normally covering 100 the dispensing slot 14 from which issues one or more paper strips as 24, 25.

The casing 11 has an arm 15 projecting through the box 10.

A cutting knife is indicated at 16 actuated by the handle 17 about the pivot 18 and fixed with the said knife and lever 20 and extending to the inside of the box 10.

The arm 15 and lever 20 are connected by the rod 21 such that the swinging of the han- 110

dle 17 in the direction of the arrow 26 cuts the paper and also swings open the cover or casing 11.

When the casing is in the closed position of Figs. 2 and 5 the knife occupies the full line positions of Figs. 2 and 4 and when the knife is operated the cover is raised to the position of Fig. 3 to deliver the record strips, the knife being shifted from the full line position of Fig. 4 in the direction of the arrow 26 until it occupies the dotted line position of Fig. 2, thereby cutting the paper strip as it has been delivered through the slot 14.

Before more paper can be delivered through this slot the knife must be returned to the full line position closing the casing 11.

It will now be seen that to secure the record strip from the machine the operator must cut the same, and that after the knife has once started to cut, more paper cannot be withdrawn from the machine until the cut is completed.

In other words every amount of fluid dispensed from the pump will be indicated by or upon the paper strip and in order to deliver this paper strip to the customer, the operator must cut the same, and the length cut off, on which is recorded by the mechanism of our co-pending application to which reference is made above, will indicate the exact amount of fluid dispensed by the pump in the transaction.

We claim:

1. Safety means for fluid dispensing

pumps, comprising a box and mechanism within said box adapted to operate synchronously with said pump and adapted to advance a plurality of paper strip records of each dispensing transaction, a compartment into which said strips are advanced, a hinged cover normally closing said compartment, hand operated cutting means on said box adapted to cut the advanced strips, and operating connections between the cutting means and the cover constructed and adapted to hold the cover closed except when the cutting means is employed to cut the strips and upon said cutting to open the cover and deliver the strips. 35

2. Safety means for fluid dispensing pumps as set forth in claim 1 wherein said operating connections are within the box, and the compartment and the cover and the knife are outside of said box. 50

3. Safety means for fluid dispensing pumps as set forth in claim 1 wherein said operating connections comprise a pivot pin extending through said box on which said cutting means is fixed external to said box, a lever fixed on said pivot within said box, a hinge between said cover and said box, an arm from said cover extending within said box and a connecting rod between the arm and the lever, whereby when the cutting means is operated the cover is opened releasing the cut strips. 55

ARTHUR R. MASON.
OTTO C. FAILING.
